UNITED STATES PATENT OFFICE.

JOHN WALTER MAY, OF BELMONT, MASSACHUSETTS, ASSIGNOR, BY DIRECT AND MESNE ASSIGNMENTS, TO MAY UNIVERSAL LAST CORPORATION, OF BOSTON, MASSACHUSETTS, A CORPORATION OF MASSACHUSETTS.

LAST.

Application filed December 31, 1924. Serial No. 759,201.

This invention relates to lasts of that type which are divided transversely thereby to form a fore part and a heel part and in which the heel part is movably connected to the fore part to facilitate the placing the last into a shoe and its removal therefrom.

One familiar type of divided last is that which is known to the trade generally as a "hinged" last. In such a last the heel part and the toe part are pivotally connected together so as to permit the heel part to swing upwardly when the last is to be removed from the shoe.

Another type of divided last is illustrated in my Patent No. 1,496,091, dated June 3rd, 1924. This form of last is divided transversely in two places to form the toe part, the heel part and an intermediate wedge-shaped part which is movable transversely of the last and the heel part and toe part are connected by a connecting member which permits them freely to move bodily toward and from each other in the direction of the length of the last.

The hinged last has the advantage that when it is unlocked the heel part can be swung upwardly out of the shoe which tends to facilitate the removal of the last from the shoe, but it has the disadvantage that in the upward swinging movement of the heel part the latter has a sliding motion over the counter of the shoe and, therefore, in order to swing the heel part of the last upwardly sufficient force must be employed to overcome the friction of the counter against the heel part. When a shoe is lasted the leather is drawn tightly about the last which increases the frictional engagement between the last and the counter portion of the shoe and necessitates the application of considerable force to swing the heel part of the last upwardly. It sometimes happens that the frictional engagement between the heel part of the last and the counter portion of the shoe is such that in breaking the hinged last the shoe is liable to be damaged.

A last such as shown in my above-mentioned patent has the advantage that when it is unlocked the heel part can be moved bodily forward and toward the toe part in the direction of the length of the last thus carrying it away from and entirely out of contact with the counter of the shoe. The last

shown in the above-mentioned patent, however, is rigid transversely so that the heel part thereof cannot be lifted or swung upwardly independently of the fore part.

It is one of the objects of my present invention to provide an improved last which embodies the advantageous features of both types of lasts in that the heel part is capable of being bodily moved freely toward the fore part to positively shorten the last and in which the heel part and fore part are pivotally connected together so as to permit the heel part to swing upwardly independently of the fore part in removing the last from the shoe.

In order to give an understanding of the invention I have illustrated in the drawings a selected embodiment thereof which will now be described after which the novel features will be pointed out in the appended claims.

Fig. 1 of the drawings is a longitudinal section through a last embodying my invention and showing it in extended position;

Fig. 2 is a similar view showing it in shortened position;

Fig. 3 is a section on the line 3—3, Fig. 2. 80
My improved last is divided so as to form the fore part 1 and the heel part 2 and an intermediate part 3 which is shown as wider at the top than at the bottom. The heel part and fore part are connected by a connecting member which permits them to move bodily toward and from each other and also permits the heel part to have a swinging movement.

In the preferred form of my invention this connecting member is in the form of a telescopic member comprising the two sections 4 and 5 that have a telescopic relation. The section 4 is shown in the form of a bar or arm which telescopes into the member 5, the latter being tubular in shape.

The telescopic member 5 is shown as having a slot 8 extending longitudinally thereof in which operates a pin or projection 9 extending from the arm 10, this pin and slot serving to limit the telescoping movement of the connecting member.

This connecting member is preferably rigidly secured to either the fore part or the heel part of the last and pivotally secured to the other part of the last. In the con-

struction shown the rigid connection is between the telescopic member and the fore part of the last and the pivotal connection is between said member and the heel part of the last. The member 4 is shown as having a head 6 which sets within a groove or kerf formed in the fore part 1 and which is rigidly anchored in place by rivets or pins 7 thus rigidly securing the arm 4 to the fore part 1.

The heel part 2 is shown as pivotally connected to the telescopic section 5 by means of a suitable pivot pin 10, said heel part being formed with a kerf or recess 20 in which 15 the end of the telescopic section 5 is received.

The intermediate section 3 is shown as having a central opening 11 extending therethrough in which the telescopic member is received. The opening 11 in the section 3 has sufficient dimension transversely of the last to permit said member 3 to move vertically from the operative lengthened position shown in Fig. 1 to the position shown 25 in Fig. 2. With this construction the intermediate section 3 is permanently connected to the other parts of the last or is non-detachable therefrom and has a limited movement transversely of the last.

30 When the last is in use the intermediate section is in its operative position shown in Fig. 1 and the telescopic connection is fully extended, the pin 9 bearing against the left hand end of the slot 8. The last 35 is locked in this position by means similar to that shown in my Patent No. 1,496,091, dated June 3, 1924, and which comprises a spring pressed locking pin 12 carried by the intermediate member 3 and adapted to 40 engage an opening 13 in a plate 14 that is secured to the front face of the heel section 2.

When the last is thus in its lengthened 45 position the faces of the intermediate section 3 bear firmly against the faces of the toe section and heel section and since the intermediate section is locked in this position by the locking pin 12 the resultant last structure will be one which is amply rigid 50 to withstand any pressures to which the last may be subjected in the making of a shoe.

As a further means of stiffening the last and enabling it to withstand the heavy pressure of such machines as levelling machines, sole laying machines and similar machines I provide means for locking the intermediate member 3 to the fore part of the last thus obviating any possibility of the last 60 opening at the joint between the fore part and intermediate part. The intermediate part 3 has a pin 21 extending transversely therethrough which is adapted to engage in a notch 22 formed in the upper face of 65 the arm 4 when the last is in extended po-

sition as shown in Fig. 1. This pin and notch serve to tie the intermediate part 3 and fore part together and prevents their giving or yielding away from each other when a heavy pressure is applied to the bottom of the last.

In order to remove the last from the shoe the locking pin 12 is withdrawn from the opening 13 in the plate 14 thus releasing the intermediate member 3, which then may move transversely into a position shown in Fig. 2 thus allowing the heel part of the last to freely move bodily forwardly with the result that the last is positively shortened.

In fact, with the construction shown the shortening of the last may be a very considerable amount as indicated by the two dotted line positions shown in Fig. 2. This positive shortening of the last removes all the strain on the shoe to which it was subjected by the last when in fully extended condition and the last is then simply lying in the shoe in a loose manner with the heel part separated from the counter 4 of the shoe. The last may then be removed from the shoe by swinging the heel part upwardly as shown in Fig. 2, the amount of swinging movement of which the heel is capable being determined somewhat by the amount to which the last is shortened. Since, however, the last is simply loosely lying in the shoe and not under any strain the amount which the heel swings relative to the shortening of the last will depend somewhat upon the nature of the shoe. The removal of the last is made easy because it is positively shortened and all strain is taken from it before the heel part is swung upwardly.

As is well known a last is usually much wider at the bottom of the heel portion than at the top thereof, especially in a woman's shoe, and, therefore, in the operation of removing a last from the shoe the wider portion of the last at the bottom of the heel has to be withdrawn through the narrower opening at the top of the shoe. A last which has the capability of shortening longitudinally independently of the swinging movement of the heel part is much easier to remove from a shoe having a narrow opening at the top of the heel than a last in which the heel has a swinging movement only.

Furthermore my improved last is of special advantage in the re-lasting operation involved in the manufacture of turned shoes. Because of the fact that the last can shorten positively a very considerable amount it is very easy to insert it into the shoe for the re-lasting operation after the shoe has been turned and this can be done without distorting or injuring the shoe in any way. When the last has been thus inserted the forcing of the intermediate member 3 into 130

its operative position simply lengthens the last longitudinally and thus stretches the upper over the last without any slipping movement of the heel part of the last on the counter portion of the shoe such as is involved in swinging the heel part downwardly into the shoe.

The locking pin 12 can be released in various ways and I have herein shown for 10 this purpose a releasing member 15 which can be moved forwardly thereby to release the locking pin by means of a suitable implement inserted through the opening 16 in the wall of the usual thimble 17 that 15 is located in the heel part.

I claim:

1. A last having a fore part, a heel part, and a telescopic member permanently connecting said parts and operating to limit 20 the movement of said parts away from each other, said telescopic member comprising two sections having a telescopic relation, one section being rigidly secured to the fore part of the last, and the other section being pivotally secured to the heel part, whereby said last may be shortened either by moving the heel part toward the fore part as far as the structure will permit, or by partially contracting the telescopic section and then 30 swinging the heel part about its pivot.

2. A last comprising a fore part, a heel part, an intermediate wedge-shaped part extending from the top to the bottom of the last and having a limited movement transversely thereof, a telescopic member permanently connecting the heel part and the fore part and which permits them to move freely toward and from each other in the direction of the length of the last, thereby to 35 lengthen and shorten the last, said telescopic member being constructed to limit the movement of the heel part and toe part away from each other, said intermediate part when in operative position holding the last 40 lengthened to the extent permitted by the telescopic member, and the heel part being pivoted to said telescopic member, whereby the last may be shortened after the wedge-shaped part has been moved transversely of 45 the last either by moving the heel part toward the fore part in the direction of the length of the last as far as permitted by said wedge-shaped part or by giving the heel part a slight movement toward the fore part 50 and then swinging the heel part about its pivot.

3. A last comprising a fore part, a heel part, an intermediate wedge-shaped part having a limited movement transversely of 55 the last, a telescopic member permanently connecting the heel part and fore part and which permits them freely to move toward

and from each other in the direction of the length of the last but limits the extending movement, one of said parts being pivoted to 65 said telescopic connection, and means to lock the last in extended relation.

4. A last having a fore part, a heel part and a telescopic member permanently connecting said parts, said member comprising 70 two sections having a telescopic relation, one section being rigidly secured to one part of the last and the other section being pivotally secured to the other part of the last.

5. A last having a fore part, a heel part 75 and a telescopic member permanently connecting said parts, said member comprising two non-separable sections having a telescopic relation, one section being rigidly secured to the fore part of the last and the 80 other section being pivotally secured to the heel part of the last.

6. A last comprising a fore part, a heel part, a wedge-shaped intermediate part movable transversely of the last, a telescopic 85 member having two non-separable sections, one section thereof rigidly secured to the toe part of the last and the other section pivotally secured to the heel part of the last, and means for locking the intermediate part 90 to the first-named section of said telescopic member.

7. A last comprising a fore part, a heel part and a wedge-shaped intermediate part, a telescopic member connecting said parts 95 and comprising an arm rigid with the fore part and projecting toward the heel part and a co-operating member pivotally secured to the heel part with which said arm telescopes, said arm having a notch, and a pin carried 100 by the intermediate part and adapted to engage said notch when the last is in its lengthened condition.

8. A last comprising a fore part, a heel part, a wedge-shaped intermediate part extending from the top to the bottom of the last, a telescopic member permanently connecting the heel part and fore part and permitting them to move freely toward and from each other in the direction of the 105 length of the last thereby to lengthen and shorten the last, said telescopic member extending through an opening in the intermediate part, whereby said intermediate part is non-detachable from the other parts and 110 has a limited movement transversely of the last, one section of the telescopic member being rigidly secured to the fore part of the last and the other section being pivotally secured to the heel part of the last. 115

In testimony whereof, I have signed my name to this specification.

JOHN WALTER MAY.
